POWER LEVER AND ENGINE USING
THE SAME

Rufus C. Hof, La Bolt, S. Dak.

Application February 18, 1947, Serial No. 729,381

6 Claims. (Cl. 74—44)

1

This invention relates to power developing levers and mechanical linkages.

An object of the invention is to provide a power developing lever which may be employed in a mechanical linkage including an engine crank-shaft and piston, for increasing the power obtained during the cycle of operation thereof.

Another object of the invention is to provide a mechanical movement of a lever, fulcrum and crank-shaft, which develops surplus power.

A further object of the invention is to provide a hydraulic engine which is particularly adapted for incorporation therein of my improved power lever.

Still another object of the invention is to provide a mechanical movement including a power lever, which is simple in design, inexpensive to manufacture, and which is highly efficient in operation, for the purpose intended.

Other objects and advantages of the invention will become apparent from the following description of a preferred embodiment thereof as illustrated in the accompanying drawings, and in which:

Figure 1 is a top plan view of a hydraulic engine incorporating my invention, the view partly sectioned to show the construction.

Figure 2 is a sectional elevation taken on line 2—2 of Figure 1.

Figure 3 is an elevational view of the power lever and its cooperating parts.

Figure 4 is a sectional elevation of the power lever assembly shown in Figure 3.

Figure 5 is a sectional plan view taken on line 5—5 of Figure 3.

Figure 6 is a partly diagrammatic elevational view showing the positions of the parts of the mechanical movement when the piston is at the bottom of its stroke.

Figure 7 is a partly diagrammatic elevational view showing the positions of the parts of the mechanical movement when the piston is at an intermediate position of its stroke.

Figure 8 is a partly diagrammatic elevational view showing the positions of the parts of the mechanical movement when the piston is at the top of its stroke, and

Figure 9 is a face view of the power lever, illustrating the engagement of its stub shafts in the two notches provided for that purpose.

In order to understand clearly the nature of the invention and the best means for carrying it out, reference may now be had to the drawings, in which like numerals denote similar parts throughout the several views.

2

As seen best in Figures 3, 4, and 5, the power developing lever 10 is divided longitudinally into two halves 12 and 14, in order to engage an engine crankshaft 16. The design of the lever in two halves allows for assembling over a four-crank shaft. The long end 17 of the lever 10 contains a built in stub shaft 18 extending out of one side thereof, as seen in Figure 4, the shaft 18 being formed of complementary halves integral with the lever halves 12 and 14, the shaft being thus receivable in the connecting rod bearing 20.

The short end 22 of the lever 10 contains two integral stub shafts 24 and 26 to engage with the fulcrum notches 28 and 30 respectively. The crank bearing 32 on the power lever 10 is cylindrically extended on each side of the lever to hold it in position on the crank and to provide ample bearing surface. The fulcrum 34 contains the two notches 28 and 30 as shown, these being adapted to receive the stub shafts 24 and 26 of the power lever. These notches on the fulcrum are spaced to take up one inch or one-third of the distance from the center of the crank shaft to the center of the crank, which in this case would be three inches. The other two inches, or two-thirds distance of the length of the crank is taken up by the short end of the power lever or the two stub shafts 24 and 26 on the end of the lever.

The distance of the two stub shafts is thus on a line two inches from the center of the crank bearing on the lever. The force exerted on the fulcrum by the lever is taken care of by a carrier built on top of the fulcrum 34 with two bevel edged wheels 36 rotatable thereon as shown in Figure 4, each wheel operating between a separate pair of flange edged tracks 38, allowing the fulcrum to shift from left to right as seen in Figures 6 through 8, and back again, and thus maintain a constant coordination of the fulcrum with the lever 10, which is necessary and assured by the action of two links 40 and 42, and one bracket track 44.

The right hand side operating link 40 operates with one end bearing on lever shaft 26, the opposite end of the link bearing being supported and held securely at one point on the fulcrum by a stub shaft on the bracket 46 and consequently the link swings with the required necessary movement of the lever and assures the return of the lever stub shaft 26 to the fulcrum notch 30.

The left hand link 42 operates on the opposite or left hand side of the fulcrum and is connected to the left hand side bracket 48 and lever shaft

24, and assures the return of the lever stub shaft 24 to the fulcrum notch 28. The two links may also assist the notches in support of lever pressure.

When the lever moves downward to a horizontal position shown in Figures 2 and 7, these links do not maintain a close coordination of lever and fulcrum, this being taken care of by another connection, the bracket track 44 by engaging a roller 50 and 52 on the crank. The roller halves 50 and 52 are held on the crank by any suitable means such as by wire 54 being wound on a section of the roller as shown in Figure 4, with ends of the wire keyed and soldered into suitable holes in the number 50 half of the roller.

The separate or removable section 56 on the bracket end of the bracket track allows for removal or assembling of the bracket track over the crank. Three stud-bolts 58 attached in bracket 48 are inserted through fulcrum holes, bracket 46, bracket track 44 and section 56, and serve to securely attach all brackets to the fulcrum, being also secured and aligned accurately by machined shoulders 60, and by V-grooved surfaces at 62. The tracks 38 are preferably insulated for shock and sound absorption by composition rubber gaskets 64.

According to one embodiment of the invention, the parts shown may be made to fit and operate on a three inch length crank-arm to produce a six inch stroke. The short end of the lever would then have an operating length of two inches between the lever crank bearing and the fulcrum, and the long end of the lever to receive the power force applied would have a length of six inches between the lever crank bearing and the connecting rod shaft 18.

These leverage specifications with one pound of power force applied on the long end of the power lever 10 produces three pounds of pressure on the short end of the lever, which is absorbed by the fulcrum, and the crank arm on the crank shaft receives a pressure weight of three pounds plus about one-third of a pound surplus. This is produced by the one pound of pressure on the long end of the power lever 10.

There are additional possibilities of altering the dimensions, as by lengthening or shortening the long end of the lever to give more or less surplus power with a given amount of force applied to the connecting rod shaft 18. For example, the power lever may be made with its long end about eighteen inches long between the crank bearing 32 and the connecting rod shaft 18, which increases the surplus power to about one pound for one pound of pressure on the lever connecting rod shaft 18. There is also the possibility of designing the short end of the power lever, fulcrum and fulcrum notches for a longer or shorter crank-arm to meet various requirements, as a longer crank-arm permits of enlarging and strengthening of the lever stub shafts, fulcrum, the connecting links, brackets, and the bracket-track parts.

The need and requirement for a weight or force to apply on the power lever down stroke and then instant removal to complete the upward stroke, permits of using a new type hydraulic engine, illustrated in Figures 1 and 2, which can provide this force by power-pistons and valve control. About twenty per cent larger capacity pump-pistons to return and maintain pressure are driven by the power crank shaft. Surplus power control is accomplished by open-

ing or closing the pressure port holes to the intake valves by a throttle or governor.

As seen in Figures 1 and 2, and in fragment in Figures 6, 7, and 8, there is a power-piston intake valve 66, intake-cam 68, exhaust-valve 70, and exhaust-cam 72. Pump-piston 74 has an intake-valve 76, intake-cam 78, exhaust-valve 80, and an exhaust-cam 82.

Numerical 84 shows the pressure manifold connected with pump-piston outlet valve 89, which conveys pressure to the throttle-tube 86 inside tube 88. The exhaust from power-piston 90 is through exhaust-valve 70 and manifold 92 connected to pipe 94 leading gravity oil to the pump-piston intake-valves 76 along with supply from the gravity tank outlet 96.

The broken out section of Figure 1 along broken line 97 shows two power-lever assemblies in their working position on the crank shaft. The throttle and governor tube being the high point of the engine, the top view is drawn in cross-section in full lines, with covered lines in dots or dashes.

The power lever crank-shaft through sprocket chain 98, connects and drives the pump-pistons crank shaft 99 which it encircles and engages by means of a sprocket wheel 95. Chain 100 connects the power lever crank shaft with and drives the power cylinder cam shaft 101 to properly time and operate all the power cylinder valves. Chain 102 connects the pump-piston crank shaft with and drives the pump cylinder cam shaft 103 to properly time and operate all the pump cylinder valves.

The cylinder and pump-piston 74 has an enlarged capacity in excess of the power-piston 90 of about twenty percent, to return and maintain or increase the pressure for the power piston. The pressure is controlled by the pressure valve outlet 104 to gravity tank 106. The gravity tank 106 along with the exhaust oil from the power piston 90, fills the pump piston cylinder 74 on the intake stroke.

Surplus power is controlled by controlling the pressure flow as provided by a tube or sleeve 86 containing port holes to open or close the port holes in the pressure manifold pipe or tube 88 leading to the intake valve of the power piston, by means of a throttle lever 108, which rotates the sleeve to open or close the port holes. Control by governor is provided by arm 110 connected by a shaft to fly-valves 112 provided for each of the power cylinder intake ports.

Figures 6, 7, and 8 show elevational views of the positions of the power lever 10 and connecting rod 114 and the parts associated therewith during various stages of the cycle. Notch 116 in the connecting rod provides clearance for the bracket track roller 50 and 52.

Figure 6 shows the power lever 10 connected to the power-piston 90 by the connecting rod 114 and having moved down the line 118 by the hydraulic pressure on the piston 90 to complete the first step of the cycle of the power stroke. In the first half of the power stroke, the power-lever 10 pivots or hinges on the shaft 26 in the fulcrum notch 30 to the horizontal position. With the power lever at the horizontal position, both of the power lever shafts 24 and 26 are seated in the fulcrum notches 28 and 30. As the power lever leaves the horizontal position to move down the power stroke, it pivots, or hinges, on shaft 24 in the fulcrum notch 28. Numerical 120 marks the line point where the intake valve 66 opens for the power stroke.

Numeral 122 marks the line point where the intake valve 66 closes to end the power stroke. Power lever shaft 18, connected to the bearing on the connecting rod 114, moves down with the crank on the crank shaft along the line 118 from 120 to 122 and has completed the power stroke. Intake valve 66 has closed as the cam 68 has revolved from under the intake valve-stem roller 124 at the proper instant.

The line 126 in Figure 6, drawn from the center of the power lever shaft 18 to the center of fulcrum notch 28 and power lever shaft 24, shows the off center position of the crank shaft bearing 32 which now drives the power lever and forces it to reverse movement and the connecting rod bearing on shaft 18 to follow along line 128. The double curve in line 128 shown in Figures 7 and 8 is caused by the reversed power lever being driven from or along from the circle of the revolving crank of the crank shaft.

In Figure 7, with bracket track 44 assembled in operating position, the bracket 46 is partly behind the bracket track 44 as shown by dotted lines. About half the length of link 40 is shown by dotted lines behind the bracket 46. The power lever 10 is shown by dotted lines behind the fulcrum 34 and the bracket track 44.

The exhaust stroke of the power-lever shaft 18 has followed along the line 128 and is shown half completed in Figure 7 with exhaust valve 70 at open position as the cam 72 has properly engaged the exhaust valve-stem roller 130. In the exhaust stroke movement of the power lever upward and back to the horizontal position shown in Figure 7, the shaft 24 on the power lever pivots, or hinges, in the fulcrum notch 28 and the shaft 26 returns to the fulcrum notch 30. In the movement made by the power lever from the position shown in Figure 7 to the position of Figure 8, the power lever shaft 26 pivots, or hinges, in the fulcrum notch 30.

Figure 8 shows the exhaust stroke has followed along the second curved line 128 to complete the second step of the cycle or revolution of the crank shaft and power lever, with the exhaust valve 70 closed as the cam 72 is revolved from under the exhaust valve stem roller 130.

The three Figures 6, 7, and 8 as drawn, show the schematic power stroke and exhaust stroke working to complete the cycle required to operate the power-lever as being accomplished by the hydraulic engine. Each following revolution of the crank shaft and power lever repeats the above described movements.

In Figure 7, the bracket track 44 is shown engaging the crank roller 50-52, which at this point serves to hold the fulcrum 34 and power lever 10 together in their operating movements. The three Figures 6, 7, and 8 show views of the link 40 in its changing operating positions and which, with link 42 on the opposite side of the fulcrum 34 serves to hold the power lever 10 and the fulcrum 34 together through all their required movements. The fulcrum as seen has moved to one extreme end position between its tracks 38 in Figure 7 in the exhaust stroke. The other extreme end position of the fulcrum on the tracks 38 occurs when driven by the power lever 10 in the half completed power stroke on line 118 as in Figure 6.

These three Figures 6, 7 and 8, also show the reason why it is possible to use the small size and off center position of the cylinder 132, with the clearance design of the connecting rod 114, for this length of stroke.

Although I have described a preferred embodiment of my invention in specific terms, it is to be understood that various changes may be made in size, shape, materials and arrangement without departing from the spirit and scope of the invention as claimed.

I claim:

1. A power lever for use in an engine having a piston movable in a cylinder, with one end of a connecting rod engaging the piston, and having a rotatable crankshaft, said power lever comprising an elongated body having a crank pin bearing aperture formed intermediate its end and dividing the lever body into a long end portion and a short end portion, said long end portion being adapted for pivotal engagement with the lower end of the engine connecting rod, said short end portion having a pair of laterally spaced and projecting stub shafts for pivotal engagement at least one at a time with matching recesses formed in a fulcrum portion of the engine housing.
2. An engine comprising a housing having a cylinder formed therein, a piston slidable in said cylinder, a rotatable crank-shaft in said housing, a connecting rod having one end engaging said piston, a fulcrum member movably engaging said engine housing, and having a pair of fulcrum notches formed therein, and a power lever having a crank-shaft bearing formed intermediate its ends and dividing the lever body into a long end portion and a short end portion, said long end portion being adapted for pivotal engagement with the lower end of the engine connecting rod, said short end portion having a pair of laterally spaced and projecting stub shafts for pivotal engagement at least one at a time with said fulcrum notches formed in said fulcrum as said parts undergo an engine cycle.
3. An engine comprising a housing having a cylinder formed therein, a piston slidable in said cylinder, a rotatable crank-shaft in said housing, a connecting rod having one end engaging said piston, a fulcrum member movably engaging said engine housing and constrained into movement perpendicular to the axis of rotation of the crank-shaft, said fulcrum member having an extension with a pair of spaced fulcrum notches formed therein, and a power lever comprising an elongated lever body with a bearing aperture formed therein intermediate its ends for reception of the said crank-shaft, said bearing aperture dividing said lever body into a long end portion and a short end portion, said long end portion being adapted for pivotal engagement with the lower end of the connecting rod, said short end portion having a pair of spaced stub shafts projecting laterally therefrom, said stub shafts being constructed and arranged for engagement at least one at a time with said fulcrum notches as said engine parts pass through an engine cycle.
4. An engine comprising a housing having a plurality of cylinders formed therein, a piston slidable in each cylinder, a rotatable crank-shaft journaled in said housing, a connecting rod connected at one end to each of said pistons, a plurality of fulcrum members movably engaging said engine housing and constrained into movement in a direction perpendicular to the axis of rotation of the engine crank-shafts, each fulcrum member having an extension with a pair of spaced fulcrum notches formed therein, a plurality of power levers each comprising an elongated lever body with a bearing aperture formed therein intermediate its ends for reception of said

crank-shaft, said bearing aperture dividing each lever body into a long end portion and a short end portion, said long end portion having a first stub shaft projecting therefrom for pivotal engagement with the lower end of the corresponding connecting rod, said short end portion having a pair of spaced second stub shafts projecting laterally therefrom, said second stub shafts being constructed and arranged for engagement at least one at a time with said fulcrum notches as said engine undergoes a cycle of operation.

5. A power lever for use in an engine having a piston movable in a cylinder, with one end of a connecting rod engaging the piston, and having a rotatable crank-shaft, said power lever comprising an elongated lever body having a bearing aperture formed therein intermediate its ends, for engaging said engine crank-shaft and dividing the lever body into a long end portion and a short end portion, said long end portion having a first stub shaft extending therefrom for pivotal engagement with the lower end of said connecting rod, said short end portion having a pair of spaced second stub shafts projecting therefrom, and a fulcrum member movably engaging said engine housing and constrained into motion perpendicular to the axis of rotation of the crank-shaft, and having an extension with a pair of fulcrum notches formed therein for the reception, at least one at a time, of said second stub shafts as the engine passes through an engine cycle, said fulcrum notches being spaced to take up one-third of the distance from the center of the crank-shaft to the center of the crank, the other

two-thirds of the length of the crank being taken up by the short end of the power lever.

6. A power lever for use in an engine having a piston movable in a cylinder, with one end of a connecting rod engaging the piston, and having a rotatable crank-shaft journaled in the engine housing, said power lever comprising an elongated lever body having a bearing aperture formed intermediate its ends for engagement with said crank-shaft and dividing the lever body into a long end portion and a short end portion, said long end portion having a first stub shaft projecting therefrom for pivotal engagement with the lower end of the said connecting rod, a pair of spaced second stub shafts projecting from said short end portion adjacent the end thereof, said lever body being split longitudinally, means for securing the halves of said lever body together, a fulcrum member movably engaging said engine housing and constrained into motion perpendicular to the axis of rotation of the crank-shaft, and having an extension with a pair of fulcrum notches formed therein for the reception, at least one at a time, of said second stub shafts as the engine passes through an engine cycle, said fulcrum notches being spaced to take up one-third of the distance from the center of the crank-shaft to the center of the crank, the other two-thirds of the length of the crank being taken up by the distance between a line joining said second stub shafts and the center of said bearing aperture, and bracket track and link means for maintaining constant co-ordination of the fulcrum with said power lever.

RUFUS C. HOF.
